UNITED STATES PATENT OFFICE.

WILLIAM DOUGLAS McGANN, OF CHICAGO, ILLINOIS.

CORRESPONDENCE-PACKET.

1,356,078.

Specification of Letters Patent. Patented Oct. 19, 1920.

Application filed May 4, 1918. Serial No. 232,449.

To all whom it may concern:

Be it known that I, WILLIAM DOUGLAS McGANN, a citizen of the United States, residing at Chicago, in the county of Cook 5 and State of Illinois, have invented an Improvement in Correspondence-Packets, of which the following is a specification.

The object of my invention is to provide an improved way of packaging letter paper 10 and envelopes so as to make a compact, unitary, self-wrapped package. The object is further to provide an attractive correspondence packet for the special convenience of soldiers and travelers, the packet being 15 easily stowed in a knapsack or traveling bag, available for mailing without additional wrapping, and, when opened, adapted to provide a support for writing.

The invention will be described with reference to the annexed drawings, and particularly pointed out in the claims.

In the drawings,

Figure 1 is a front view of a packet embodying my invention, having substantially 25 the appearance of an ordinary envelop such as is used for mailing photographs and the like.

Fig. 2 is a back view of the same.

Fig. 3 is an interior view of the packet 30 fully opened, revealing the face side of the writing paper.

Fig. 4 is a horizontal section on the line $\alpha-\alpha$ of Fig. 3.

Fig. 5 is a perspective view of the opened 35 packet, indicating the manner of folding.

Fig. 6 is a view of the packet partially folded.

Fig. 7 is a vertical cross-section of the folded packet.

Fig. 8 is a detail view in vertical section 40 showing a modified means of attaching the writing paper to the wrapper.

1 denotes a pad of writing paper and 2-2 are a couple of packs of letter envelopes 45 bound with ordinary paper bands 3. Said paper and envelopes are packaged in a wrapper 4 formed as a backing for the pad and with envelop-retaining side flaps 5 and an upper end flap 6. The wrapper may be 50 made of relatively heavy paper or other appropriate material. The paper pad, preferably formed with a flexible back 1^a, is affixed to the inner side of the wrapper by pasting or gumming the upper portion of 55 the pad thereto; and the packs of envelopes

are attached to the respective side flaps by pasting or gumming the paper bands 3 thereto. The main body of the wrapper is slightly larger than the paper pad to provide a desirable margin, and the packs of 60 envelopes are retained on the side flaps sufficiently offset from the main body of the wrapper to provide clearance for folding, the several flaps being foldable on the dotted double lines 4^a indicated in Fig. 3. 65

The package is folded in the manner illustrated in Figs. 5, 6 and 7. The pad is first folded upon itself, the side flaps with the attached envelopes are then folded upon the pad, the lower portion of the wrapper folded upon said flaps, and the top flap then folded over the free end of the wrapper and suitably fastened. A well known form of fastening means is shown consisting of the string 7 attached to a paper disk 8 on the 70 end flap 6, the string being passed around the package and having its end twisted around the disk.

If desired the side flaps with the attached 75 envelopes may be folded upon the face of the pad, and the lower part of the latter together with the lower part of the wrapper folded upon the flaps, and the top flap then folded down and fastened; though the manner of folding first described is preferable 80 because it makes a more compact packet.

The wrapper constitutes an outer envelop, with the writing paper and envelopes affixed to and infolded with the flaps of the outer envelop, thus making a neat, compact 90 package with the parts of the wrapper and contents so folded as to provide considerable stiffness and protect against crumpling. The package is available for delivery from the store or for posting in the mails without additional wrapping, and may be stowed in a restricted space in the knapsack or traveling bag. When opened, the wrapper affords a convenient support for the writing 95 pad and retains the pad and envelopes in proper relative position, avoiding misplacement and dropping of the envelopes.

It may be desirable to design the package for refilling with paper and envelopes, 100 and in that event the paper pad may have its back provided with a tongue 1^b adapted to engage a pocket 4^b formed on the inner face of the wrapper, as shown in Fig. 8, 105 and the envelop retaining bands may be 110 made of more durable material than paper,

as for instance elastic or semi-elastic material, and permanently glued or otherwise affixed to the side flaps of the wrapper.

With variations in the character and 5 quantity of the writing paper and envelopes, and in the style of the wrapper, the packet may be designed as a convenient correspondence outfit for the home or office, or as a souvenir, advertising novelty, or for various 10 other special purposes.

Having thus described my invention, I claim:

1. A correspondence packet comprising writing paper and envelopes, and an outside 15 wrapper forming a backing for the writing paper and having a pair of opposite envelop-supporting side flaps and an end flap, said side flaps with the attached envelopes

being folded upon the writing paper, and the lower portion of said wrapper folded 20 over said flaps and the end flap folded over the free edge of the wrapper.

2. A correspondence packet comprising writing paper and envelopes, and an outside wrapper forming a backing for the writing 25 paper and having a pair of opposite envelop-supporting side flaps and an end flap, said side flaps with the attached envelopes being folded upon the writing paper, and the lower portion of said wrapper folded over 30 said flaps and the end flap folded over the free edge of the wrapper, and fastening means for said end flap.

In testimony whereof, I have signed my name to this specification.

WILLIAM DOUGLAS McGANN.
